UNITED STATES PATENT OFFICE.

GARABED G. HEGHINIAN, OF NEW YORK, N. Y.

MOLDING-PRESS.

No. 834,671.

Specification of Letters Patent.

Patented Oct. 30, 1906.

Application filed February 23, 1906. Serial No. 302,357.

To all whom it may concern:

Be it known that I, GARABED G. HEGHINIAN, a citizen of the United States, and a resident of the city of New York, borough of Brooklyn, in the county of Kings and State of New York, have invented certain new and useful Improvements in Molding-Presses, of which the following is a specification.

This invention relates to improvements in presses, and particularly to improvements in presses for automatically molding, shaping, and compressing blocks—such as paving-blocks, tiles, building bricks or blocks, briquets, &c.—from an asphalt mixture or clay or a cement mixture or any other suitable material.

The object of my invention is to provide a new and improved machine of this kind which is simple in construction, strong and durable, which properly shapes and firmly compresses the blocks, and at all times feeds the material to the molds as required.

In the accompanying drawings, in which like letters of reference indicate like parts in all the figures, Figure 1 is a vertical transverse sectional view of my improved press, parts being broken away. Fig. 2 is a vertical longitudinal sectional view of the same on a slightly-reduced scale. Fig. 3 is a plan view of the machine, parts being in section. Fig. 4 is a detail view of the same. Fig. 5 is a horizontal sectional view on the line $x-x$ of Fig. 4 on an enlarged scale. Fig. 6 shows several parts in perspective view.

The entire machine is supported on a heavy cast base A, provided with brackets in which the main driving-shaft B is journaled. This shaft B carries a fly-wheel B', a tight-belt pulley B², and a loose-belt pulley B³. On this shaft B a worm C is fixed, which engages a worm-wheel C', secured on the horizontal cam-shaft D, which is journaled in the body of the machine and in a standard D' at one end of the base and preferably made integral with the base. This cam-shaft carries a main operating-cam E, which is preferably provided with a removable or interchangeable shoe E', which can act on the antifriction-rollers F and F', located, respectively, vertically above and vertically below the cam-shaft D. The roller F above the cam-shaft is mounted in the forked lower end of a vertically-movable plunger G, which is guided in its up and down movements in a suitably-constructed guide G', formed of sections of the body part of the machine. The

roller F', located beneath the cam-shaft D, is mounted in a fork of a cross-piece or yoke H, the ends of which enter slots I, formed in the flattened portions I' of two reciprocating rods J, which are guided in their vertical movements in the top of the machine, and these rods are also guided by their flattened slotted lower portions I', which move up and down in grooves I² of the machine frame or body. The rods J are connected at their upper ends by a yoke or cross-piece L, from which a plunger L' extends downward. It thus follows that for one complete revolution of the cam-shaft D in the direction indicated by the arrow in Fig. 1 the plunger G is first forced upward, and later on the plunger L' is forced downward by the action of the cam E on the lower cross-piece H and the upper cross-piece L, connected therewith by the rods J. The plunger G descends under the action of its own weight, and thus its roller F is at all times kept in contact with the edge of the cam E; but provision must be made for raising the upper plunger L' after it has been forced down.

As shown in Fig. 4, the cam-shaft D passes through the slots I in the lower flattened portions of the rods J in order to permit such rods to reciprocate, and at said flattened portions of the rods J a cam K is secured to the cam-shaft D, one at each side of the machine, and the edge of this cam is in contact with a roller K', projecting laterally from each rod J.

As shown in Fig. 4, the cams K are so shaped that approximately five-eighths of the circumference serves for lifting the rods J, and the balance of the edges is cut away, so as to permit the cam E to force down the upper plunger, and with it the rods J. Two dies M and M' are provided, the die M being located above the plunger G and the die M' being located beneath the plunger L', and within these dies the respective plungers compress the material to form the asphalt blocks. The mold or die M is not in contact with the top of the guide G', but is separated from the same a distance equal to the thickness of a feed-slide N, which can slide horizontally—that is, transversely to the direction of movement to the plunger G—on a table formed by the top surface of the guide G'. A similar feed-slide N' is mounted to reciprocate horizontally on the table formed by the top of the die or mold M'. A double anvil O, fitting within the dies or molds M and M', is mounted between them in such a manner that it

can be reciprocated vertically or moved up and down, and this anvil O is provided with lateral stops O' for the purpose of limiting its movements. These lateral stops are so located that when they rest upon the top of the lower die or mold M the lower end of the anvil O is flush with the under side of the lower mold or die M, and when these stops rest against the under side of the upper die or mold M' the top or upper end of the anvil is flush with the upper surface of the upper die or mold M'. This anvil not only acts as a double anvil, but also acts as a double ejector for ejecting or forcing the asphalt blocks compressed in the molds M and M', respectively, out of said molds, so that these ejected blocks can be moved laterally on the table formed by the upper surface of the upper mold M' and the guide G'. The feed-slide N is provided with an opening of the same dimensions as the opening in the dies M and M' and of the respective plungers G and L', and the height of these feed-slides is greater than that of the completed block, because the material before it has been compressed occupies more space in height than a compressed block. The feed-slide N is provided with a bracket N', and at its outer end this bracket is pivotally connected with the lower end of a cross-arm P, secured on a rock-shaft P', suitably mounted in brackets of the frame of the machine.

The upper feed-slide N' is provided with two openings Q and Q', both of the same size as the opening in the feed-slide N, and these openings are arranged one in advance of the other in the direction of movement of said slide N'. Said upper feed-slide N' rests upon a bracket Q'', projecting laterally from the frame of the machine, and the outer end of this upper slide is pivotally connected with the upper end of the cross-arm P on the rock-shaft P'. This shaft P' is provided with a crank-arm P'', which is pivotally connected with a connecting-rod R, the forked lower end R' of which straddles the crank-shaft D, as shown in Fig. 4. Adjacent to one of the cams K a roller R' on a pin projecting laterally from the connecting-rod R passes into a cam-groove R'', formed in one side face of the cam K, as shown in Fig. 4, so that as the cam-shaft rotates the connecting-rod R and the rock-shaft P' and cross-pieces P and R will remain at rest for part of the rotation of the cam-shaft and for the balance of this rotation are operated in such a manner as to rock the rock-shaft P' and cross-piece P, thereby at suitable intervals shifting the feed-slides N and N' always in opposite directions, but leaving them at rest between said shifting periods in a manner and for a purpose that will appear later on.

The material from which the blocks are to be made, preferably asphalt, is fed into a hopper S, containing a screw conveyer S' for

feeding the material downward into a bottom discharge-chute S''. This screw conveyer or hopper S is driven by beveled gearing from the shaft D and a shaft S'', which is provided at its outer ends with a belt-pulley (not shown) and over which a belt is passed, which also passes over one of a series of pulleys a on the cam-shaft D. Pulleys a of different sizes are provided for the purpose of controlling the proper feed—that is, feeding more or less material, as may be required. This chute S'' extends from the bottom of the hopper down to the lower feed-slide N and terminates in the transverse opening in which the slide N reciprocates. Above the top of the upper slide N' side openings are formed in said feed-shute S'', through which the upper feed-slide N' can reciprocate. As shown, the feed-chute S'' throughout its entire length is provided with a steam-jacket b, so as to prevent the asphalt mixture from congealing or binding.

A U-shaped yoke T is secured at its upper open end to each side of the anvil O and extends downward, its closed lower end being curved to surround the inner side of the corresponding vertical rod J. A pin V' projects from each side of the plunger G and extends through a vertical slot V in the guide G', and these pins are normally about one inch below the lower closed ends of the yokes for the purpose of lifting or raising the yoke, and thereby discharging the block made in the upper die. A flat boss W is formed on the inner side of each rod J, and on it two latches T are pivoted to swing toward and from each other, and these latches have straight top edges and downwardly and inwardly inclined bottom and outer side edges, and the latches of each pair are pressed from each other by a spring z. Two pins T' project from the inner side of each rod J between the side shanks of the corresponding yoke T, as shown in Fig. 5.

A block T'', having two upwardly-extending spurs or prongs t, is secured to the outer side of each guide G', as shown in Fig. 2. These parts are provided to insure a positive movement of the anvil O, as will be explained hereinafter.

The operation of the machine is as follows: With the parts in the positions shown in Fig. 1 and the shaft D rotating in the direction of the arrow, Fig. 1, a completed asphalt block d, formed and compressed in the upper die M', is within said die and rests upon the upper part of the anvil O. There is also a full charge of asphalt mixture in the lower feed-slide N, which mixture is in line with the lower plunger G, die M, and the anvil O. The upper feed-slide N' has just been withdrawn, so that its opening Q is in line with the chute S'; but there is no material in this opening, as the conveyer has not yet had time to force down the material into the said

opening Q. The opening Q' is filled with asphalt mixture. As the shaft D continues to rotate in the direction of the arrow its cam E forces up the lower plunger G, wherefore by the charge of asphalt in the lower feed-slide N is forced up and out of this feed-slide and into the lower die M, and this charge forces upward the anvil O until its shoulders O' rest against the under side of the upper die M'. By this movement of the plunger G the material pushed out of the lower feed-slide N is compressed within the die M between the bottom of the anvil and the upper end of the plunger G, and by the upward movement of the anvil O the completed block d in the upper die M' is pushed out of said die and up to the top of said die. During this time the material has been fed into the opening Q of the feed-slide N, which opening Q is in line with the chute S'. By this time, also, the cam E has passed to the left of the roller F, Fig. 1, and the plunger G descends under the action of its own weight. By that time the cam has acted to rock the rock-shaft P', and thereby the upper feed-slide N' is moved to the left and pushes the completed block resting on the top of the upper die M' to the left upon a suitable conveyer-belt. (Not shown.) Thereby the charge fed into the opening Q of the slide N' is moved under the plunger L', and the charge in the opening Q' of the slide N' is brought in line with the feed-chute. At the same time that the upper slide N' is moved to the left the lower feed-slide N is moved to the right, so that its opening will be in line with the feed-chute, and a charge of asphalt is fed into this lower feed-slide N. The feed-slides then remain at rest for a time, and the cam E acts on the lower roller F' and forces down the upper plunger L', which forces the charge from the opening Q of the slide N', which opening is now in line with the upper die M', downward and compresses this charge in the die M' and upon the upper end of the anvil O, and at the same time the anvil O is forced downward until its stops O' rest on the top of the lower die M. Thereby the completed block made in the lower die M, as described, is ejected from this lower die by the descending anvil O upon the table, formed by the top of the guide G'. By this time the cam E has passed to the right of the lower roller F' and the cams K have raised the upper plunger L' into the position shown in Fig. 1 and the rock-shaft P' has been operated in such a manner as to shift the upper feed-slide N' to the right and the lower feed-slide N to the left, whereby the completed block resting on the table formed by the top of the guide G' has been moved to the left and upon a conveyer-belt, (not shown,) and at the same time the upper feed-slide has been moved to the right, and all parts are again in the position shown in Fig. 1.

When the yokes T are forced upward, their lower cross-pieces press the latches T' together until these cross-pieces are above the latches T', and then the latches snap outward and the bottom cross-pieces of the yokes rest upon and are supported by the straight top edges of the latches.

When the rods J move downward, their pins T' bear on the bottom cross-pieces of the yokes, and thereby the yokes are forced down and pull down the anvil O; but these bottom cross-pieces are still above the latches T'. When the latches T' arrive at the blocks T², the prongs t engage the lower beveled edges of the latches and press the latches toward each other and keep them in this position during the time the rods J rise and while the yokes are at rest, thus permitting the latches T to pass up between the side shanks of the yoke and above the bottom cross-pieces of the same and into the positions shown in Fig. 2, and by the time these latches have passed above the bottom cross-pieces the latches are released from the block T and can spread. During the next upward movement of the yokes the bottom cross-pieces again press the latches together and pass into position above the latches, as previously described. It will thus be seen that for each rotation of the cam-shaft two blocks are made, first one by the upper plunger and then one by the lower plunger, and that then the completed blocks are successively pushed out of the path of the plungers by the feed-slides, the feed-slides at the same time delivering material for fresh blocks.

It should be noted that the material passing into the opening Q' of the upper feed-slide N' is not used for making a block in the upper die, but is only temporarily removed out of alignment with the column of material in the chute, so as to permit the opening Q being filled, and this material in the opening Q' is then again brought into alignment with the column of material in the feed-chute to be gradually forced down into the lower feed-slide N.

It should also be noted that the anvil O acts as a double anvil—that is, each end acts as an anvil and each end also acts as an ejector for ejecting the block made and compressed upon this end of the anvil. In order that the material may be evenly distributed in the openings of the feed-slides, the vertical axis of the conveyer-screw in the bottom part of the hopper is moved a trifle to one side of the central axis of the hopper in the direction in which the feed-slides convey the material from the chute to the dies. As the slides move from right to left there is a tendency to condense the material in the right-hand end or rear end of the slide by the frictional contact of the material with the face on which it slides, or in other words, by friction the material will be crowded

toward the right-hand end of the aperture in the slide, and thus the material in the slide will be more dense at the right-hand end than at the left-hand end. Thereby the axis 5 conveyer-screw is slightly moved toward the left, so as to make the material descending in the left-hand side of the chute more dense than at the right-hand side, and thus counterbalance the effect of compression by 10 the movement of the chute. Each plunger works during three-eighths of the revolution and rests during five-eighths of the revolution at the main cam-shaft. The box is reshifted one-fourth of a revolution and remains at 15 rest for the corresponding three-fourths of a revolution, one-eighth of a revolution moving in one direction and one-eighth for moving in the reverse direction, so that each box is under the hopper about three-eighths of a 20 revolution.

Having described my invention, what I claim as new, and desire to secure by Letters Patent, is—

1. In a molding-press, the combination 25 with two dies and a plunger for each die, which dies and plungers are all arranged in line, of a feed-slide for each die, which feed-slides are mounted to move at right angles to the direction of movement of the plungers, a 30 feed-chute, the axis of which is vertical to the slides, and means for shifting said feed-slides automatically in opposite directions, substantially as set forth.

2. In a molding-press, the combination 35 with two dies and a plunger for each die, which dies and plungers are all arranged in line, of a feed-chute, the axis of which is parallel with the line of movement of the plungers, a feed-slide for each die, which 40 feed-slides in their movement cross the axis of the feed-chute, a cross-arm pivotally connected with the two slides, a crank-shaft on which said cross-arm is secured, a main cam-shaft for operating the plungers and means 45 for rocking the rock crank-shaft from said main cam-shaft, substantially as set forth.

3. In a molding-press, the combination 50 with two dies and a plunger for each die, which dies and plungers are all arranged in line, of a feed-chute, the axis of which is parallel with the line of movement of the 55 plungers, a feed-slide beneath one die and the bottom of the said chute, which feed-slide is mounted to reciprocate horizontally beneath said die and the lower end of said feed-chute, a second feed-slide mounted to slide upon the top of the other die, and also 60 transversely to said feed-chute and means for moving said slides, substantially as set forth.

4. In a molding-press, the combination 65 with two dies and a plunger for each die, which dies and plungers are all arranged in line, of a feed-chute, the axis of which is parallel with the line of movement of the

plungers, a feed-slide beneath one die and the bottom of the said chute, which feed-slide is mounted to reciprocate horizontally beneath said die and the lower end of said feed-chute, a second feed-slide mounted to 70 slide upon the top of the other die, and also transversely to said feed-chute and means for moving said slides, the lower feed-slide having a single opening for receiving the material and the upper slide having two 75 openings for receiving material, said openings being arranged in line in the direction of movement of said upper slide, substantially as set forth.

5. In a molding-press, the combination 80 with two dies and a plunger for each die, which dies and plungers are all arranged in line, a feed-chute, the axis of which is parallel with the line of movement of the plungers, a feed-slide beneath one die and the lower 85 end of the feed-chute, which slide has an opening of the same dimension as the plunger and its die, and which opening extends from top to bottom of said feed-slide, an additional feed-slide mounted to move over 90 the top die and at right angles to the feed-chute, which upper slide has two openings arranged in line in the direction of the movement of the slide, both openings extending entirely through the slide and being of the 95 same dimensions as the die and plunger, substantially as set forth.

6. In a molding-press, the combination 100 with two dies and a plunger for each die, which dies and plungers are all arranged in line, of a feed-chute, the axis of which is parallel with the line of movement of the plungers, a feed-slide beneath one die and the lower end of the feed-chute, which slide has an opening of the same dimension as the 105 plunger and its die, and which opening extends from top to bottom of said feed-slide, an additional feed-slide mounted to move over the top die and at right angles to the feed-chute, which upper slide has two 110 openings arranged in line in the direction of the movement of the slide, both openings extending entirely through the slide and being of the same dimensions as the die and plunger, and a bracket for supporting the upper slide, 115 substantially as set forth.

7. In a molding-press, the combination 120 with two dies and a plunger for each die, which dies and plungers are all arranged in line, of a feed-chute, the axis of which is parallel with the line of movement of the plungers, a feed-slide beneath one die and the bottom of the said chute, which feed-slide is mounted to reciprocate horizontally beneath 125 said die and the lower end of said feed-chute, a second feed-slide mounted to slide upon the top of the other die, and also transversely to said feed-chute and means for moving said slides, the lower feed-slide having a single 130 opening for receiving the material and the

upper slide having two openings for receiving material, said openings being arranged in line in the direction of movement of said upper slide, a rock-shaft, a cross-arm on said rock-shaft, the ends of which cross-arm are pivotally connected with the slides and means for rocking the said rock-shaft, substantially as set forth.

8. In a molding-press, the combination with two dies and a plunger for each die, which dies and plungers are all arranged in line, of a shaft, a cam on said shaft for operating said plungers, a feed-chute, the axis of which is parallel with the line of movement of the plungers, a hopper on the upper end of said feed-chute, a screw conveyer in said hopper and means for operating said screw conveyer from the cam-shaft, and feed-slides mounted to reciprocate transversely to the feed-chute for feeding the material from said chute to the dies, substantially as set forth.

9. In a molding-press, the combination with two dies and a plunger for each die, which dies and plungers are all arranged in line, of a feed-chute, slides for transferring the material from the feed-chute to the dies and which slides move at right angles to the feed-chute, a vertical conveyer-screw for forcing the material down through said chute, the axis of said conveyer-screw being slightly to one side of the central axis of the chute in the direction in which the material is fed from the chute to the dies, substantially as set forth.

35 10. In a molding-press, the combination with two dies, one above the other and having openings extending entirely through the same, of a plunger for the upper die, a plunger for the lower die, which dies and plungers are all arranged in line, a cam-shaft for moving said plungers, an anvil located between the dies and extending into both and also mounted to move up and down in line with the plungers, a feed-slide beneath the lower die, and a feed-slide above the upper die, both of said feed-slides having openings which extend entirely through the slides and are of the same dimensions as the dies and plungers, substantially as set forth.

50 11. In a molding-press, the combination with two dies, one above the other and having openings extending entirely through the same, of a plunger for the upper die, a plunger for the lower die, which dies and plungers are all arranged in line, a cam-shaft for moving said plungers, an anvil located between the dies and extending into both and also mounted to move up and down in line with the plungers, a feed-slide beneath the lower die, and a feed-slide above the upper die, both of said feed-slides having openings

which extend entirely through the slides and are of the same dimensions as the dies and plungers, and means for operating said feed-slides from the cam-shaft, substantially as set forth.

5 12. In a molding-press, the combination with two dies arranged vertically in line, of a plunger for each die, which plungers are arranged in line and are mounted to move toward and from each other, means for operating said plungers, a movable anvil located in the dies and between the plungers, and means for raising said anvil from the lower plunger, substantially as set forth.

75 13. In a molding-press, the combination with two dies arranged vertically in line, of a plunger for each die, which plungers are arranged in line and are mounted to move toward and from each other, means for operating said plungers, a movable anvil located in the dies and between the plungers, and means for raising said anvil from the lower plunger, by the means for moving the upper plunger, substantially as set forth.

84 14. In a molding-press, the combination with two dies arranged in line, of a plunger for each die, which plungers are arranged in line and are mounted to move toward and from each other, means for operating said plungers, a movable anvil located in the dies and between the plungers, and means for lowering the anvil as set forth.

95 15. In a molding-press, the combination with two vertical dies and a vertical movable plunger for each, of an anvil located between the two plungers and adapted to co-operate alternately with each, of a feeder for each die and means for operating said feeder, substantially as set forth.

16. In a molding-press, the combination with two dies, a plunger and feed-slide for each die, of an anvil common to both dies, said plungers acting alternately in and out of their respective feed-slides, thereby pressing the material contained in said feed-slides against the common anvil and whereby the block previously made in one die is first discharged from its die before the block is compressed between the common anvil and the other plunger in the die pertaining to this other plunger, substantially as set forth.

Signed at New York city, in the county of New York and State of New York, this 21st day of February, A. D. 1906.

GARABED G. HEGHINIAN.
